FLOODLIGHT

Buell Moore, Houston, Tex., assignor to Esquire, Inc.,
New York, N.Y., a corporation of Delaware

Filed Apr. 10, 1969, Ser. No. 16,666

Term of patent 14 years

Int. Cl. D26—02

U.S. Cl. D48—20

FIG. 1

FIG. 2

FIG. 3

FIG. 4

FIG. 1 is a front view of a floodlight embodying my design;

FIG. 2 is a back view of the floodlight;

FIG. 3 is a perspective view of the floodlight, as seen from the front and one side thereof; and

FIG. 4 is another perspective view of the floodlight, as seen from the front and the other side thereof.

The smooth surface on the front of the floodlight is a window.

The interior slanted surfaces reflect images from the upper and lower horizontally disposed lenses, which images are visible when the floodlight is frontally viewed as in FIG. 1.

I claim:

The ornamental design for a floodlight, substantially as shown and described.
